UNITED STATES PATENT OFFICE.

ERNEST DE WITT R. GARDEN, OF LOS ANGELES, CALIFORNIA.

IMPLEMENT FOR FORMING METAL BACKS FOR ARTIFICIAL TEETH.

1,113,325.

Specification of Letters Patent.

Patented Oct. 13, 1914.

Application filed September 29, 1913. Serial No. 792,471.

To all whom it may concern:

Be it known that I, ERNEST DE WITT R. GARDEN, citizen of the United States, residing at Los Angeles, in the county of Los Angeles and State of California, have invented certain new and useful Improvements in Implements for Forming Metal Backs for Artificial Teeth, of which the following is a full and clear specification.

10 My invention relates to improvements in implements for forming metal backs for artificial teeth in which a metal back is formed complete in a single operation, and consists of certain novel features of construction and arrangement of mechanical parts which are fully described in the following specification and pointed out in the claims.

15 The object of this invention is to produce a simple, cheap and efficient implement, which will enable the individual dentist to easily and readily form these metal backs at a very nominal cost.

20 With this end in view I produce a very simple and efficient implement by simply hinging a pair of handled levers together at one end, thereby forming an effective clamping device, upon the inner opposing surfaces of which are mounted the coacting members 25 of centralizing the springs *s*, *s*, which are well illustrated in the accompanying drawing, in which—

25 Figure 1 is an elevation of the assembled implement in the position occupied at the completion of the first step in the operation of forming the metal back. Fig. 2, is a top view of the lower handled lever of the implement as illustrated in Fig. 1, the handle portion being broken away. Fig. 3, is a bottom view of the top member as illustrated in Fig. 1, the handle portion also being broken away. Fig. 4, is a view in cross section of Fig. 1, taken on line X, X. Fig. 5, is a view in cross section of Fig. 1, taken on line Y, Y. Figs. 6, 7 and 8, are respectively a plan, end and side elevation of the metal back when formed complete and ready for the operation of mounting the teeth upon them. Figs. 9 and 10, are respectively a plan and

side elevation of a tooth mounted upon the metal back, ready for trimming the edges of the metal preparatory to burnishing them down against the edge of the tooth. Figs. 6, 7, 8, 9, and 10, form no part of the present invention, but are shown to illustrate the finished product of the implement, and its method of application.

Similar letters refer to similar parts throughout the several views.

30 The implement is composed principally of two handled levers A, and B, which are hinged together at C. Forming levers D, and E, are pivotally mounted upon a common center, upon the handled lever A, as seen at F. A spring-chamber G, is formed in, and transversely of the handled lever A, as shown, and elongated slots *a*, and *a*, are formed through the upper wall thereof, as shown in Fig. 4. Pins *b*, and *b*, are rigidly secured to, and project downwardly from the forming levers D, and E, through the slots *a*, and *a*, and terminate within the spring-chamber G, and is well illustrated in Fig. 4. The relative positions of the slots *a*, *a*, and the pins *b*, *b*, serve to limit the outward movement of the forming levers D, and E. A spring *c*, is interposed between the pins *b*, *b*, within the spring-chamber G, and is of such tension or resistance as to hold forming levers D, and E, lightly in their open position. The working faces of the forming levers D, and E, are tapered as shown at *d*, *d*, in Fig. 1, and are also beveled or undercut as shown in Figs. 4, and 5, at *e*, *e*. A lug H, is rigidly secured to, and projects upwardly from, the handled lever A, to the height of, and centrally of the forming levers D, and E, and the face *h*, of the said lug is formed upon a radius from the pivotal center of the forming levers D, and E, and designated by the letter F. The forming levers D, and E, are notched to receive and encircle the lug H, and the said notches are designated by the letters *i*, *i*, the surfaces *j*, *j*, are of the same radius as the face *h*, of the lug H, and is fitted to work over the same freely but closely. Pins *k*, *k*, are rigidly secured to, and project up-

wardly from, the forming levers D, and E, for a purpose which will be fully herein-after explained.

A male forming member I is secured to 5 the handled lever B, by collar screws m, m. The male forming member I, is shown in Figs. 1, 3, 4 and 5, and the collar-screws are illustrated in Figs. 1, and 5. The collar-screws m, m, are fitted to slide freely in the 10 holes n, n, in the handled lever B, the purpose of which will be fully explained later on. A housing J, is secured to the outer side of the handled lever B, by screws o, o, shown in Figs. 1, and 4. The housing J, is 15 provided with two spring-chambers p, p, shown in Fig. 5.

The collar-screws m, m, are provided with extensions r, r, which extend upwardly into the spring-chambers p, p, for the purpose 20 of centralizing the springs s, s, which are confined within the spring-chambers p, p, and rest upon the collars t, t, of the collar-screws m, m, with sufficient tension to overcome the resistance of the first operation of 25 forming the metal backs, these backs being illustrated in Figs. 6, 7, 8, 9 and 10. The springs s, s, also serve the purpose of keeping the male forming member I projected downward to its normal position, until the 30 completion of the first stage of the forming operation, and allowing it to recede during the second and final operation of forming the metal back referred to above. The springs s, s, impart a resiliency to the action 35 of the male forming member I, which is highly beneficial in the forming up of articles from sheet metals.

A yoke K, having downwardly projecting limbs L, L, which are in turn provided with 40 beveled faces u, u, is secured to the handled lever B, by screws v, v, and is located forward of the male forming member I.

Having completed the mechanical construction of the implement I will now proceed to describe its operation; opening the 45 handled levers A, and B, such distance as will admit of conveniently placing a small square or rectangular piece of metal of the required dimensions and thickness over the 50 levers D, and E, and against the pins k, k, and the handled levers started upon their closing movement, in the course of which, the male forming member I contacts with the metal to be formed, and carries it down 55 between the levers D, and E, which operation causes the metal to conform to the inner tapered face of the said male forming member I. When the male forming member I, has carried the metal down between the 60 levers D, and E, to its predetermined depth, a further movement of the handle members causes the beveled faces u, u, on the limbs L, L, of the yoke K, to contact with the outer edges of the levers D, and E, and a

continued closing pressure of the handled 65 levers A, and B, results in swinging the said levers inwardly and closing the metal snugly against the beveled sides of the male forming member I, thereby completing the operation of forming the metal back. 70

Having thus described my invention what I claim and desire to secure by Letters Patent is—

1. In an implement for forming metal backs for artificial teeth, a pair of hinged 75 handled levers, a pair of pivoted levers mounted upon one of said levers, and a male forming member mounted upon the other handled lever, and adapted to coöperate with the pivoted levers upon the other lever, 80 substantially as described.

2. In an implement of the character described, for forming metal backs for artificial teeth, a pair of handled levers hinged at their outer ends, a pair of levers pivotally mounted upon one of said handled levers, a chamber in said handled lever, and means within said chamber for holding the said levers normally open, a male forming member mounted upon the other handled 90 lever, and coacting with the pivoted levers upon the first mentioned lever, means for closing the said pivoted levers secured to the second mentioned handled lever all arranged and operating substantially as shown 95 and described.

3. In an implement of the character described, for forming metal backs for artificial teeth, a pair of hinged handled levers, a pair of levers, having tapered and beveled faces, pivotally mounted upon one of said hinged handled levers, a transverse chamber in said hinged handled lever, longitudinal slots perforating the wall of said chamber, pins in said levers projecting downwardly through the said slots into said chamber, a spring in 105 said chamber, and under tension between said pins, and holding the said levers normally open, a male forming member yieldingly mounted upon the other of said hinged 110 handled levers, and coacting with the said pivoted levers upon the first mentioned hinged handled lever, a yoke, having downwardly projecting limbs, said limbs being provided with beveled faces, said yoke secured to the second mentioned hinged 115 handled lever, and adapted to contact with and swing the pivoted levers upon the first mentioned hinged handled lever inwardly, substantially as shown and described, and 120 for the purpose specified.

4. In an implement of the character described, for forming metal backs for artificial teeth, a pair of hinged handled levers, a pair of spring opened levers pivoted 125 upon one of said hinged handled levers, a male forming member, secured to the other hinged handled lever, by collar-screws slid-

ably passing through said hinged handled lever, collars upon said collar-screws to limit the movement of the said male forming member inwardly, spring chambers mounted 5 upon the outer side of the said hinged handled member, and springs in said chambers, and exerting tension upon the collar portion of said collar-screws to hold the male forming member in its inwardly nor-

mal position substantially as shown and de- 10 scribed and for the purpose specified.

In testimony whereof I affix my signature in the presence of two witnesses.

ERNEST DE WITT R. GARDEN.
